FREQUENCY MODULATOR

John M. Carter and John R. Boykin, Baltimore,
Md., assignors to Westinghouse Electric Corporation,
East Pittsburgh, Pa., a corporation of Pennsylvania

Application December 26, 1946, Serial No. 718,498

16 Claims. (Cl. 332—29)

1 Our invention relates to electric discharge apparatus, and it has particular relation to apparatus for producing frequency-modulated oscillations.

Apparatus constructed in accordance with the teachings of the prior art of which we are aware, is exemplified by the Fichandler Patent 2,000,584. Fichandler discloses a system for producing frequency-modulated oscillations comprising a frequency-determining network, across which a variable resistance and a reactance are connected. The components of the network and the resistance and reactance are so set that variation of the resistance over a small range produces variation of the reactance of the whole network without accompanying variation of resistance. Fichandler shows the variable resistance as a three-electrode tube, the grid potential of which is varied to vary the plate resistance.

We have found that a transmitter including the Fichandler system has several undesirable features. The output of a transmitter is distorted. It is marred by hum such as arises from undesired pulsations of a 60-cycle power supply and by other sounds not introduced by the modulating source. Amplitude modulations are also at times present in the output.

It is, accordingly, an object of our invention to provide a frequency-modulation system which shall produce signals substantially free of distortion.

Another object of our invention is to provide a frequency-modulation system which shall produce signals substantially free of alternating-current hum.

A further object of our invention is to provide a frequency-modulation system in which extraneous sounds are substantially suppressed.

Still another object of our invention is to provide a frequency-modulation system which shall produce signals substantially free of amplitude modulations.

More generally stated, it is an object of our invention to provide a frequency-modulation transmitter of simple structure, in which extraneous signals shall be suppressed.

Our invention arises from our realization that the sensitive point in a frequency-modulation transmitter is the network at which the modulations are introduced. Beyond this point the frequency multiplication is high (in excess of nine). Distortion arising from interelectrode capacity at the modulation network, alternating-current hum, microphonic noises and amplitude modulations introduced at the network are highly

2 amplified by the multiplication effect and materially deteriorate the output.

The interelectrode capacity of Fichandler's resistance tube is substantial, as is also the capacity to ground of the electrodes. These capacities introduce distortion into the modulations impressed on the frequency-determining network. The amplitude of the distortions is small, but the distortions are highly amplified by the frequency multiplication and deteriorate the output of the transmitter.

Fichandler's resistance tube requires a filament supply which is customarily of the rectified alternating-current type. Although this supply is filtered, the filament current retains pulsations of low magnitude. The pulsations highly amplified, introduce undesirable hum in the output.

The resistance tube has electrodes which have 20 a tendency to vibrate. The sounds which are produced in the ordinary transmitting station and in particular in the vicinity of an ordinary communication equipment (aboard a plane or ship or in a police car) tend to cause the electrodes to execute vibrations of minute amplitude. The output of the modulator is highly amplified, and the minute vibrations are converted into substantial microphonic sounds.

In Fichandler's system energy from the oscillation generator flows back with facility to the modulating network. The variable resistance tube (34, Fig. 5), having substantial anode grid capacity, provides a relatively low impedance feedback path. The regenerative effect produced 35 by the feedback amplified by multiplication also deteriorates the output.

In accordance with our invention, we provide a frequency-modulation network comprising a crystal of the type used in crystal rectifiers. 40 Such crystals are commonly composed of germanium, silicon, galena or similar substance. As the current through such crystals varies, the resistance of the crystal varies. This variation in resistance is introduced in a frequency determining network to produce frequency modulations.

Feedback of energy from the oscillation generator to the modulating network is suppressed by a crystal rectifier interposed in the modulation network. This rectifier has low capacity and effectively blocks the flow of feedback oscillation.

The novel features that we consider characteristic of our invention are set forth with particularity in the appended claims. The inven-

tion itself, however, both as to its origination and its method of operation together with additional objects and advantages thereof, will best be understood from the following description of a specific embodiment when read in connection with the accompanying drawing, in which:

Figure 1 is a diagrammatic view showing a frequency-modulation system in accordance with our invention,

Fig. 2 is a view in section showing a crystal assembly used in the preferred practice of our invention,

Fig. 3 is a diagrammatic view showing a modification of our invention,

Fig. 4 is a diagrammatic view showing a further modification of our invention,

Fig. 5 is a diagrammatic view showing still another modification of our invention, and

Fig. 6 is a diagrammatic view showing a still further modification of our invention.

The apparatus shown in Fig. 1 comprises a generator of electrical oscillations 5 including an electric discharge device 7 which has an anode 9, a cathode 11 and a grid 13.

Anode potential is supplied to the discharge device from a source (not shown) through a resonant network 15 connected to the anode 9. The grid 13 is biased negative with respect to the cathode 11 by operation of a biasing network including a resistor 17 shunted by a capacitor 19. The biasing network is connected between the grid 13 and a frequency-determining network 21. The latter comprises an inductor 23 and a variable capacitor 25, and is connected to ground at the terminal remote from the biasing network. The cathode 11 is connected to the inductor 23 at a point intermediate its terminals. The portion of the inductor between the cathode 11 and ground introduces a regenerative potential, causing the circuit including the discharge device 7 to oscillate.

Across the frequency-determining network 21, a modulation network including a coupling capacitor 27 and a crystal assembly 29 is connected.

The crystal assembly 29 is preferably a 1N34 germanium detector such as is shown in Fig. 2. It comprises a cylindrical ceramic tube 30 closed at the ends by caps 32. From the center of one cap, a small metallic projection 34 extends. A particle 36 of crystalline germanium or other suitable material is secured to the projection. From the other cap 32, a fine wire 38 extends. The tip of the wire engages the germanium particle. The assembly is approximately $\frac{1}{4}$ " in diameter and $\frac{5}{8}$ " long and its distributed capacity is small. The essential element of the assembly is the crystal 36. The other components are provided for effecting connection with the crystal.

The crystal assembly is supplied with current from a modulating source, such as a microphone circuit 31, for example. The microphone circuit includes an output transformer 33, the secondary 35 of which is connected across the modulation network 21 through a rectifier 37. This rectifier (37) may also be a 1N34 crystal assembly. Across the secondary 35 of the transformer, a condenser 39 is connected. This condenser and the rectifier 37 in series with the secondary operate to suppress the flow of the oscillations produced in the generator through the microphone circuit 31.

Signals impressed in the microphone circuit 31 cause currents of variable magnitude to flow through the crystal 36 in the modulation net-

work. The currents vary the resistance of the crystal, thus varying the net reactive component of the frequency-determining network 21. The magnitudes of the components of the network 21, 5 the mean crystal resistance and capacity 27, are so set that the net resistive component of the frequency determining network is not varied. Accordingly, frequency modulations, but not amplitude modulations, are produced in the output of the oscillator.

The resonant network 15 in the output circuit of the discharge device 7 is tuned to a multiple of the unmodulated frequency of the oscillator. This network (15) is inductively coupled to another resonant network 41 in the control circuit of another electric discharge device 43. The latter resonant network (41) is tuned to the same frequency as the network 15 in the plate circuit of the first electric discharge device 7. The circuit 15 including the discharge device 43 thus operates as a frequency multiplier. Depending on the output frequency and amplitude desired, additional frequency multipliers and amplifiers 45 may be interposed between the multiplier (15, 41, 43) 25 just described and an output device, such as a radiating antenna 47.

The signals radiated by the antenna are free of alternating-current hum because the crystal 29 at the sensitive point in the transmitter circuit does not require filament current. Distortions and amplitude modulations are suppressed because the interelectrode capacity of the crystal 29 and its capacity to ground is small. The crystal is small and its electrodes have no tendency to be set into vibration by transmitter station sounds, and, therefore, the output signal is free of microphonic noises.

We have conducted extensive tests with our modulation circuit and have found that the crystal circuit has a usable linear responsive over a range of approximately 3 to 4 per cent of the unmodulated frequency of the oscillation generator. This linear range is substantially greater than that available for the modulation circuit in 40 which a vacuum tube is connected at the sensitive point. Accordingly, distortions in the output signal arising from deviations from linearity, are substantially less in a modulation system in accordance with our invention, than in the prior art modulation systems.

In the modifications of our invention shown in Fig. 3, the rectifier 37 in series with the secondary 35 of the microphone transformer is replaced by a reactor 49. This reactor and the capacitor 39 perform the function of suppressing oscillations from the generator 5. While our invention, in its broadest aspects, comprehends within its scope a frequency-modulation system including the reactor, the system including the rectifier 45 37 in the secondary circuit in lieu of the reactor 49 is superior and is to be preferred. The reactor has a tendency to introduce nonlinearity in the response of a modulation circuit.

In the modification of our invention shown in 65 Fig. 4, a capacitor 51 is connected in parallel with the crystal 29. This capacitor cooperates with the coupling capacitor to properly divide the voltage across the inductor 23 in the frequency-determining network 21.

Fig. 5 shows a circuit designed for high r.-f. current. In this a plurality of crystals are connected in parallel.

Fig. 6 shows a circuit in accordance with our invention designed for situations where the amplitude of the radio frequency oscillations exceeds

5

the rating of single crystals. In this case, a pair (or a plurality) of crystals 53, 55, 57 and 59 in series may be used.

Although we have shown and described certain specific embodiments of our invention, we are aware that many modifications thereof are possible. For example, the capacitor 27 may be replaced by a reactor of any other type such as an inductor. Other reactances may be correspondingly varied. For low carrier frequencies, the tube 7 may be of the gas filled type; for very high frequencies, it may be of the klystron type. In the latter case, the network 21 is a resonator. The crystal assembly 29 may in specific embodiments of my invention be of a different structure than the one disclosed. Where our invention is applied to relatively low frequency systems, a crystal assembly having larger distributed capacity and capable of conducting current of larger magnitude may be used. Our invention, therefore, is not to be restricted except insofar as is necessitated by the prior art and by the spirit of the appended claims.

We claim as our invention:

1. In combination, a generator of electrical oscillations, a frequency-determining network for said generator, a network shunting said frequency-determining network including a crystal, the resistance of which varies with the current flowing therethrough, means for varying the current flow through said crystal, and means interposed between said shunting network and said varying means for suppressing the flow of oscillations from said generator through said varying means, said suppressing means including a crystal and condenser in series.

2. In combination, a generator of electrical oscillations, a frequency-determining network for said generator, a network shunting said frequency-determining network including a crystal, the resistance of which varies with the current flowing therethrough, means for varying the current flow through said crystal, and means interposed between said shunting network and said varying means for suppressing the flow of oscillations from said generator through said varying means, said suppressing means including a crystal rectifier.

3. In combination, a generator of electrical oscillations, a frequency-determining network for said generator, a network shunting said frequency-determining network including a crystal, the resistance of which varies with the current flowing therethrough, means for varying the current flow through said crystal, and means interposed between said shunting network and said varying means for suppressing the flow of oscillations from said generator through said varying means, said suppressing means including a crystal.

4. A source of frequency-modulated oscillations comprising a generator of oscillations including a frequency-determining network, a network shunting said frequency-determining network including a crystal rectifier, means for varying the current flow through said rectifier, and another crystal rectifier interposed between said varying means and said shunting network.

5. In combination, a generator of electrical oscillations, a frequency-determining network for said generator, a network shunting said frequency-determining network including a crystal, the resistance of which varies with the current flowing therethrough, and means for varying the current flow through said crystal, the magnitudes

6

of the components of said networks being so set that the net impedance produced by variation in current flow through said crystal is of the reactive type only.

6. In combination, a resonant network, a network shunting said resonant network including a crystal, the resistance of which varies with the current flowing therethrough, and means for supplying varying current to said shunting network to vary the resistance of said shunting network thereby to vary the resonant frequency of said resonant network.

7. In combination, a generator of electrical oscillations, a frequency-determining network for said generator, a network shunting said frequency-determining network including a crystal, the resistance of which varies with the current therethrough, and connections for varying the current through said crystal in accordance with a given signal to frequency modulate said generator in accordance with said signal.

8. In combination, a generator of electrical oscillations, a frequency-determining network for said generator, a network shunting said frequency-determining network including a crystal, the resistance of which varies with the current flowing therethrough, and a reactance connected in series, and connections for varying the current through said crystal in accordance with a given signal to frequency modulate said generator in accordance with said signal.

9. In combination, a generator of electrical oscillations, a frequency-determining network for said generator, a network shunting said frequency-determining network including a crystal of the type that is electro-mechanically independent of said generator and the resistance of which varies with the current flowing therethrough, and connections for varying the current flow through said crystal.

10. In combination, a generator of electrical oscillations including a frequency-determining network, a network shunting said frequency-determining network including an electromechanically inert crystal, the resistance of which varies with the current flow therethrough, and connections for varying the current flow through said crystal.

11. In a modulation circuit, the combination of a generator of electrical oscillations, a frequency determining network for said generator, a modulation network including a crystal shunting said frequency determining network, a source of modulating signals, a modulation transformer connected to said source of modulating signals and having a secondary connected to said modulation network, and a suppressing circuit connected across said secondary.

12. In a modulation circuit, the combination of a generator of electrical oscillations, a frequency determining network for said generator, a modulation network including a crystal shunting said frequency determining network, a source of modulating signals, a modulation transformer connected to said source of modulating signals and having a secondary connected to said modulation network, and a suppressing circuit connected across said secondary including a crystal and a reactance in series.

13. The combination of a generator of electrical oscillations, a frequency determining circuit for said generator, a modulation network including a low-capacitance crystal shunting said frequency determining network, a source of modulation signals connected to said modulation net-

work, an output translating device, and a frequency multiplier connected between said generator and said output translating device and adapted to multiply the output oscillation frequency from said generator before feeding said translating device.

14. In apparatus for providing oscillations which are adapted to be frequency modulated by a modulating source, the combination of a resonant network, a modulating network including a crystal element connected to said modulating source and shunting said resonant network, the resistance of said crystal element varying with the current flowing from the modulating source through the element, and a reactance connected between said resonant network and said modulating network.

15. For use in apparatus for providing high frequency oscillations which are adapted to be frequency modulated by a modulation signal source, the combination of a frequency determining network for said oscillations, a modulating network connected between said frequency determining network and said modulation signal source, said modulating network including a crystal element having a resistance which varies with the current through the element, and a capacitor having a relatively low impedance to said high frequency oscillations and shunting said crystal element.

16. In apparatus for generating first oscillations which are adapted to be frequency modulated by second oscillations from a modulating source, the combination of a resonant network for determining the frequency of said first oscillations, and a modulating network shunting said

resonant network and connected to said modulating source, said modulating network including a crystal rectifier of the type that has an inter-electrode capacity and a capacity to ground which are small compared to the capacity of said network.
